SHEET METAL BUNDLING MACHINE

James Ferrando, South Leechburg, Pa.

Application June 11, 1948, Serial No. 32,481

2 Claims. (Cl. 153—10.5)

1

This invention relates to a novel machine of simple construction adapted for use in mashing or flattening sheet metal elements such as cans and drums for forming a compact mass capable of being readily tied into a bundle for sale as reclaimed or salvaged metal.

Numerous machines have been provided for this purpose most of which are operated by hydraulic or pneumatic means and so far as is known all of which are so large in size that they must be supported on an embedded concrete or similar foundation. Accordingly, due to the expense of conveying waste metal such as tin cans and large drums from waste piles to the locations of such machines, much of such metal is never salvaged.

It is a primary object of the present invention to provide a machine which is relatively light in weight by comparison to other machines now in use for the same purpose and which is capable of being readily transported to the location of piles of waste metal so that the flattening and bundling operation can be accomplished without transporting the metal to the machine thereby materially reducing the salvage expense.

More particularly, it is an object of the present invention to provide a machine utilizing a gravity actuated ram or impact element with novel means for raising the ram to a desired elevation for release so that sufficient force will be imparted to the ram on its down stroke for accomplishing the flattening or mashing of the metal.

Another object of the invention is to provide a novel hopper or container for receiving the metal to be flattened and into which the ram or impact member is impelled by gravity.

Still a further object of the invention is to provide a novel latch arrangement for supporting the ram in a partially elevated position to enable loading of the hopper or container through the open top thereof thereby affording an extremely simple means whereby additional metal to be flattened can be added to the hopper or container after it has been partially filled with flattened metal for completing a bundle of flattened metal of a predetermined size.

More particularly, it is a primary object of the present invention to provide a novel friction means for engaging and elevating the ram which is manually controlled to permit the ram to be released at any elevation depending upon the amount of force required.

Various other objects and advantages of the invention will hereinafter become more fully apparent from the following description of the

drawings, illustrating a presently preferred embodiment thereof, and wherein:

Figure 1 is a side elevational view of the machine;

Figure 2 is a top plan view thereof;

Figure 3 is a front elevational view, looking from right to left of Figures 1 and 2, partly in section;

Figure 4 is a view partly in side elevation and partly in vertical section taken substantially along a plane as indicated by the line 4—4 of Figure 3;

Figure 5 is a horizontal sectional view taken substantially along a plane as indicated by the line 5—5 of Figure 3, and

Figure 6 is a similar view taken substantially along a plane as indicated by the line 6—6 of Figure 3.

Referring more specifically to the drawings, the 20 bundling machine in its entirety is designated generally 7 and includes a base, designated generally 8 which is elongated and which includes side members or sills 9 connected by a plurality of cross members 10 and having platforms or 25 floor surfaces 11 and 12 at the ends thereof. The base 8 is adapted to be demountably supported on a plurality of ties or similar elements 13.

The rear platform or floor 12 provides a support for a pair of laterally spaced bearing elements 14 which are disposed thereabove and supported by depending, diverging legs 15 which are secured to said platform 12. A shaft 16 extends through and is journaled in the bearing elements 14 and has a pulley 17 fixed to each end thereof and outwardly of the bearing elements 14. A large, combination pulley and flywheel 18 is fixed to the shaft 16 between the bearing elements 14 and is adapted to be driven by an endless belt 19 on any suitable motor or engine, not shown, located beyond the end of the frame 8 provided with the platform 12 for revolving the shaft 16 and the small belt pulleys 17.

The platform or floor 11 also forms an anvil surface and has a pair of laterally spaced guide posts 20 and 21 anchored therein and rising therefrom. The guide posts 20 and 21 are provided with opposed inwardly opening grooves or channels 22.

A container or hopper, designated generally 23 is supported on the platform 11 between the lower ends of the posts 20 and 21 with said platform 11 constituting the bottom of the container 23. The container 23 includes a lower section 24 as best seen in Figure 5 including corresponding side walls 25 which are secured to the inner sides

of the posts 20 and 21, a stationary rear wall 26 and a movable front wall 27, forming the door of the container or hopper 23 and which is provided with barrel portions 28 at the ends thereof adapted to fit between the barrel portions 29 on the forward ends of the side walls 25 and which are detachably connected thereto by hinge pins 30 so that by removal of both hinge pins, the wall 27 can be removed completely or by the removal of one of the hinge pins the wall 27 can be swung on the other hinge pin as a pivot to an open position, as illustrated in dotted lines in Figure 5. The upper section 31 of the hopper 23 is secured to and supported by the posts 20 and 21 and forms an upper, flared continuation of the top of the bottom section 24 which is open at its upper end.

An open, substantially rectangular superstructure or upper frame 32 is secured to and supported by the upper ends of the posts 20 and 21 and by corresponding ends of braces 33 which are secured thereto and to the posts 20 and 21 and which extend downwardly and rearwardly therefrom and are secured at their opposite ends to the bearing elements 14, as best illustrated in Figures 1 and 2.

A pair of laterally spaced bearings 34 are secured to the upper surfaces of the side portions of the frame 32 to provide journals for a shaft 35 which extends rotatably therethrough and to each end of which is fixed a belt pulley 36. The belt pulleys 36 are spaced outwardly from the sides of the upper frame 32 and substantially in longitudinal alignment with the belt pulley 17 and an endless belt 37 is trained over the aligned pulleys 17 and 36 for driving the shaft 35 from the shaft 16. A friction roller 38 is fixed to the intermediate portion of the shaft 35 between the bearings 34 and within the open central portion of the frame 32 and a gear 39 is fixed to the shaft 35 adjacent one end of the roller 38.

The forward end of the side members of the frame 32 are provided on their upper surfaces with guide channels 40 for slidably receiving the base portions 41 of a pair of bearings 42 which project upwardly from the rear ends of said base portions or slides 41. The base portions 41 with the bearings 42 carried thereby are supported by the guides 40 for sliding movement on the top frame 32 in a direction forwardly and rearwardly of the machine 7 or toward and away from the bearings 34. A shaft 43 is journaled in the bearings 42 and is provided with a friction roller 44 corresponding to the roller 38 and longitudinally aligned therewith and a gear 45, also fixed to the shaft 43 is disposed to mesh with the gear 39. The gears 39 and 45 are provided with relatively long intermeshing teeth, for a purpose which will hereinafter become apparent.

The base members or slides 41 are provided with pins 46 which project from their rear ends and which slidably engage recesses 47 formed in and opening forwardly of the bearing members 34, as best seen in Figure 4. Each of the pins 46 carries an expansion coil spring 48 which bears against the adjacent ends of the aligned bearings 34 and 42 for urging said bearings 42 forwardly and away from the bearings 34. The opposite, forward ends of the slides or base portions 41 are provided with forwardly projecting pins or studs 49 each of which bears against a lever 50.

The levers 50 are fixed to a shaft 51 which is supported on the forward end of the top frame 32 by bearings 52 which are secured to the forward end of said frame and in which said shaft 51 is journaled. A lever 53 is fixed at one end

thereof to one end of the shaft 51 and is disposed beyond one side of the frame 32 and above a lever 54 which is pivotally mounted at its rear end on the outer side of the post 20. The lever 53 extends rearwardly from the shaft 51 and is provided with an upwardly curved free end to which one end of a rigid link 55 is pivotally connected. The opposite, lower end of the link 55 is pivotally connected to an apertured ear 56 of the lever 54. Accordingly, it will be seen that the forward, handle end of the lever 54 can be manually engaged for swinging said lever downwardly as illustrated in Figure 1 for thereby rocking the lever 53 and shaft 51 counter-clockwise to cause the levers 50 to swing rearwardly and through their engagement with the studs 49 to displace the bearings 32 rearwardly against the action of the springs 48 for moving the shaft 43, friction roller 44 and gear 45 toward the shaft 35, friction roller 38 and gear 39. A pin or stop 57, secured to the top frame 32 limits the upward swinging movement of the lever 53 and accordingly the extent to which the shaft 51 can be rocked clockwise as seen in Figure 1 by the springs 48 displacing the bearings 42 forwardly so that the gear 45 will be prevented from moving sufficiently in a forward direction for disengaging the teeth 39. As previously stated, the gears 39 and 45 are provided with relatively long teeth so that said gears will be enmeshed when the gear 45 is in either its forward or rearward position.

A ram or impact element 58 is disposed between the posts 20 and 21 and slidably connected thereto by upwardly and outwardly projecting flange members or slides 59 which slidably engage in the grooves or channels 22. The ram 58 is sized to fit into the lower section 24 of the hopper 23 and is provided with an upwardly projecting bar or shank 60 which extends upwardly through the opening of the frame 32 and between the friction rollers 38 and 44 and is of a thickness so that it will not be engaged by said rollers when the roller 44 is disposed in a forward position. However, when the lever 54 is swung downwardly, as previously described, for displacing the shaft 43 and friction roller 44 rearwardly, the bar or shank 60 will be clamped between said rollers and as said rollers are driven in opposite directions and in directions for drawing the bar 60 upwardly therethrough, as will hereinafter be described, it will be readily apparent that the ram 58 will be elevated by the rollers when the roller 44 is displaced rearwardly or into an operative position.

The posts 20 and 21 are provided with corresponding recesses 61, as best illustrated in Figure 3, each adapted to accommodate a latch element 62 which is pivotally mounted therein on a pin 63, and intermediate of its ends. The recesses 61 open inwardly and outwardly of the posts 20 and 60 21 and said latch members 62 are provided with corresponding, remote ends which project outwardly from said posts. A shaft 64 is journaled in a pair of bearings 65 which are secured to the rear sides of the posts 20 and 21 and spaced rearwardly therefrom by spacer blocks 66. The shaft 64 is provided at its ends with forwardly projecting cranks 67 which are disposed on the outer sides of the posts 20 and 21 and below the outwardly projecting, remote ends of the latch members 62, to which the free ends of the cranks 67 are connected by links 68. A weight 69 depends from the cranks 67 which is disposed outwardly of the post 21 for normally urging the cranks 67 downwardly for urging the latch members 68 in 75 a direction for causing their inner ends to swing

upwardly and toward the posts 20 and 21 into nested positions in the recesses 61, as illustrated in dotted lines in Figure 3.

A bracket 70 is attached to the forward side of the post 20 above the level of the latch members 62 and has an outwardly projecting stub shaft 71 for pivotally supporting a lever 72, adjacent one end of said lever. The rear end of the lever 72, which is disposed adjacent the pivot 71 and on the outer side of the post 20 is connected by a link 73 to the outer end of the latch member 62 of the post 20 so that by manually engaging and swinging the opposite, forward end of the lever 72 downwardly, the link 73 will be elevated for rocking said last mentioned latch member 62 in a clockwise direction as seen in Figure 3 to thereby cause the crank connected thereto to be swung upwardly for rocking the shaft 64 and the other crank 67 in the same direction to permit the other latch member 62 to swing counter-clockwise so that the inner ends of the latch members 62 will extend into the space between the posts 20 and 21 so that the ram 58 in a partially elevated position can rest on said inner ends of the latch members 62 and will be supported thereby substantially above the hopper 23 so that said hopper can be loaded with scrap metal, not shown, such as tin cans, metal drums, parts of vehicle bodies and the like. After said hopper has thus been loaded substantially to its open top, and with the belt 19 being driven in the direction as indicated by the arrow 74 in Figure 1 for revolving the pulleys 18, 17 and 36 in the direction as indicated by the arrow 75, it will be readily apparent that the shaft 35, friction roller 38 and gear 39 will also be driven in the same direction while the shaft 43, friction roller 44 and gear 45 will be driven in the opposite direction by the meshing engagement of the gears 39 and 45. Accordingly, by pressing downwardly on the forward end of the lever 54, the ram shank 60 will be frictionally engaged between the rollers 38 and 44, as previously described for elevating the ram off of the latch members 62 thereby permitting the weight 69 to rock the cranks 67 downwardly for swinging the inner ends of the latch members 62 into the recesses 61. When the ram 58 has been elevated to a desired level by the engagement of the friction rollers 48 and 44 with its shank 60, the lever 54 is released to permit the springs 48 to displace the roller 44 forwardly thereby releasing the frictional grip on the ram shank 60 so that the ram 58 can drop by gravity into the hopper 23 for compressing the metal contained therein. This operation can be repeated until all of the metal has been flattened and if the bottom section 24 is then not filled with metal, the ram 58 can be re-latched in a partially elevated position as seen in Figures 1, 3 and 4 and the upper section 31 of the hopper 23 may then be filled with additional metal and the operation repeated until the bottom section of the hopper has been completely filled. With the bottom section of the hopper completely filled with the flattened and compressed scrap metal, one of the pins 30 can be removed to permit the front wall 27 to be swung outwardly, as seen in dotted lines in Figure 5 so that the compacted metal may be removed therefrom and tied with wire into a bundle. This is preferably and most easily accomplished by stretching several strands of wire 76 from front to rear across the bottom of the hopper 23 and having the rear ends of said strands extending

upwardly and outwardly of the hopper and the forward ends thereof extending under the front wall 27. Thus, after the metal has been pressed the rear ends of the wire 76 can be passed outwardly through the open front of the hopper over the compressed metal and by then grasping both ends of each wire 76 the compacted metal can be readily removed either before or after twisting the ends of the wires for securing the bundle.

In order to provide a positive safety feature for protection of the operators, a chain or other flexible member 77 is anchored at one end thereof to the lever 54 and is adapted to be detachably connected at its opposite end to a hook or other fastening 78 secured to the post 20 above the lever 54 so that said lever can be held against being swung downwardly while the ram 58 is supported on the latch members 62 during the filling of the hopper or container 23.

It will be readily apparent that the belt pulley 18 also functions as a flywheel and that the ram 58 can be very quickly elevated so that an undue load will not be placed upon the engine or motor, not shown, utilized for driving the belt 19.

The machine 8 may be made in various sizes and is quite capable of utilizing a ram 58 weighing considerably in excess of a 1,000 pounds and yet may be constructed so that it can be readily placed upon a vehicle and moved to and set up in close proximity to a pile of scrap metal so that the flattening and bundling of the scrap metal can be accomplished without transporting the metal prior to bundling, thereby greatly reducing the salvaging expense.

Various modifications and changes are contemplated and may obviously be resorted to, without departing from the spirit or scope of the invention as hereinafter defined by the appended claims.

I claim as my invention:

1. A machine for flattening scrap metal comprising a platform, a pair of upstanding posts supported on and rising from the platform, a hopper having an open top supported on the platform and secured thereto between the lower ends of the posts, a ram slidably guided by said posts for movement toward and away from the hopper and platform and into and out of the hopper, a top frame supported on the upper ends of the posts, a driven shaft journaled in the top frame, a pair of bearings slidably supported on said top frame for movement toward and away from the driven shaft, an idler shaft journaled in said bearings, a friction roller fixed to each of said shafts, a shank projecting upwardly from said ram between the rollers, spring means for normally urging the bearing and idler shaft away from the driven shaft for normally retaining said rollers out of frictional engagement with the ram shank, manually actuated means for displacing said bearings and idler shaft toward the driven shaft for positioning the rollers in frictional engagement with the ram shaft, gear means connecting said shafts for causing the shafts to revolve with the rollers in opposite directions for drawing the ram shank upwardly therebetween when the shank is frictionally engaged by the rollers for elevating the ram, said manually actuated means being releasable for releasing the ram shank from frictional engagement with the rollers at any desired level of the ram to permit the ram to drop by gravity into the hopper, said hopper being adapted to contain scrap metal to be mashed and flattened by the impact force of the ram, latch

means swingably mounted in said posts and normally disposed in retracted, inoperative position, and manually operated means for swinging said latch means into the space between the posts for engaging under and supporting the ram in a partially elevated position and above the open top of said hopper to afford access to the open top of the hopper for filling it with scrap metal, said latch means being positively retained in an operative engagement with the ram by the weight of 10 the ram supported thereon until the ram is elevated by manual operation of said manually actuated means for positioning the rollers in frictional engagement with the ram shank.

2. A machine as in claim 1, and a safety attachment for rendering said manually actuated means 15

inoperative to prevent the ram from being elevated out of engagement with said latch means while the hopper is being charged.

JAMES FERRANDO.
